MONROWE WALTER JONES AND BERT HUDSON BRUSH, OF ARDMORE, OKLAHOMA;
SAID JONES ASSIGNOR OF HIS RIGHT TO JONES-EVERETT MACHINE COMPANY,
A CORPORATION.

COMBINED CASING AND TOOL SPEAR.

Application filed December 20, 1920. Serial No. 431,954.

To all whom it may concern:

Be it known that we, MONROWE W. JONES, and BERT H. BRUSH, citizens of the United States, and residents of Ardmore, in the county of Carter and State of Oklahoma, have invented certain new and useful Improvements in Combined Casings and Tool Spears, of which the following is a specification.

10 Our invention relates to spears used in the drilling of wells, and the purpose of our invention is the provision of a spear which is operable to simultaneously effect the withdrawal of both the well casing and drilling 15 tool or underreamer from the well, and to thereby eliminate the necessity of withdrawing the drill line through each and every joint of the casing as is necessary with spears as heretofore constructed.

20 We will describe one form of spear embodying our invention and will then point out the novel features thereof in claims.

In the accompanying drawings:

Figure 1 is a view showing in front elevation one form of spear embodying our invention.

Figure 2 is a view showing in side elevation the tool shown in Figure 1 with portions thereof broken away.

30 Figure 3 is a view similar to Figure 2 with the casing gripping members in active position and the tripping rod withdrawn from the spear.

Figure 4 is a top plan view of Figure 3.

35 Figure 5 is a vertical longitudinal sectional view of Figure 2.

Figure 6 is a transverse sectional view taken on the line 6—6 of Figure 2.

Similar reference characters refer to similar parts in each of the several views.

Referring specifically to the drawings, our invention in its present embodiment comprises a body designated generally at B, and including a wedge portion 15 and a circular head portion 16 formed integral with the lower end of the wedge portion. The upper end of the wedge portion 15 is formed with a threaded stem 17, and the lower end of the head portion 16 is formed 45 with a threaded conical stem 18. The wedge portion 15 is tapered downwardly and inwardly from its upper end to provide oppositely inclined side faces 19 which are formed with dove tailed grooves 20 adapted 50 to slidably receive therein correspondingly

shaped tongues 21 formed on casing gripping members 22.

By this arrangement it will be seen that the gripping members are slidable longitudinally on the faces 19, and that when at 60 the upper edge of the wedge portion they occupy expanded positions, while when at the lower end thereof they occupy contracted positions. The gripping members are normally biased to the active or expanded position by means of coiled expandable springs 23 which are seated within pockets 24 formed in the head portions 16. The lower ends of the gripping members 22 are formed with studs 25 that fit within 65 the upper ends of the springs 23 so as to properly center the same with respect to the gripping members and for maintaining the two properly connected at all times. The upward movement of the gripping 70 members under the action of the springs is limited or defined by abutment pins 26 arranged in spanning relation with respect to the upper ends of the grooves 20. As shown in Figures 3 and 5, the pins 26 are 75 of dovetailed formation in cross section and are adapted to fit in correspondingly shaped grooves formed in the wedge portion 15. The pins 26 are adapted to be engaged by 80 the tongues 21 of the gripping members 22 and to thereby limit the upward movement 85 of the members and at the same time prevent displacement of the members from the slots.

The gripping members 22 are adapted to 90 be locked in inactive or contracted position by means of dogs 27 pivotally supported on pins 28. As shown in Figure 2, the dogs are arranged within a suitable recess formed in the wedge portion 15 and have 95 their inner ends normally spaced apart to accommodate a tripping rod 29. As shown in Figure 6, the pins 28 are partly screw threaded and formed with grooved heads so that they may be applied and removed 100 in the manner of screws. The tripping rod 29 functions to maintain the dogs in locking position with respect to the gripping members, and in the present instance the rod is slidably fitted within an opening 105 (Figure 4) so that such rod is capable of being removed from the wedge portion of the body. For the purpose of locking the tripping rod in position between the confronting ends of the dogs 27, a locking pin 110

31 is provided which is insertible within a suitable opening formed in the body, such opening intersecting the opening 30. This pin 31 is of extremely small diameter so that it can be readily sheared, and in its applied position it extends through a suitable opening formed in the tripping rod 29 thus locking the rod in position between the dogs 27. The pin 31 is of sufficient strength 10 to normally maintain the rod in locking position but when sufficient upward pull is exerted upon the rod, the pin is sheared thus permitting the rod to be removed from between the dogs. With the dogs disengaged by the rod, it will be clear that under 15 the expandable action of these springs 23, the gripping members 22 are free to move upwardly to expanded position, the dogs swinging upon the pin 28 and thus moving 20 free of the members.

In the present instance, the gripping members have their curved surfaces formed with downwardly extending teeth 32 for the purpose of gripping the inner surface 25 of the well casing in effecting a removal of the latter, as will be hereinafter described. The upper end of the tripping rod 29 is provided with a threaded stem 29^a to which a rope socket, jars and sinker 30 bar, such as are used on a wire line cutter, may be connected to the tripping rod so that the latter can be actuated from the body 15 after the pin 31 has been sheared.

As clearly shown in Figure 5, the body 35 of the spear as well as the stems 17 and 18 are bored longitudinally to provide a duct 33 through which the drill line is adapted to be extended. The lower end of the duct 33 communicates with the interior of a 40 socket 34 threadedly connected to the stem 18. The lower end of the socket 34 is interiorly formed with a frusto-conical seat 35 in which are slidably fitted a plurality of gripping jaws 36. The gripping jaws 45 36 are tapered in thickness, and are interiorly formed with upwardly extending teeth, as clearly shown in Figure 5, the arrangement of the jaws being such that the conical seat co-acts with the same to effect 50 a constriction thereof to effect a gripping of a tool shank. The several jaws 36 are biased downwardly within the seat 35 and consequently into constricting position by means of a coiled expandible spring 37 fitted 55 within the socket 34 and interposed between the jaws and a spacing sleeve 38. This arrangement permits an upward movement and consequently a spreading of the jaws when an upward force sufficient to 60 overcome the tension of the spring 37 is exerted.

In the operation of the spear, let it be assumed that a drilling tool or underreamer is lodged in the well at the lower end of 65 the well casing and that it is desired to re-

move the tool as well as the well casing. To effect this removal, the drill line is unwound from the drum of the bull wheel to permit of the insertion of the free end of the drill line upwardly through the socket 70 34 and the duct 33 of the spear body. The spear now having been applied to the drill line, the line is again wound upon the drum of the bull wheel and by rotating the wheel at the same time holding the spear against 75 downward movement upon the drill line, the drill tool is moved as far up into the well casing as possible. With the drill tool held in this position, the spear is lowered into the well casing with the usual sand line, sliding down the drill line and into engagement with the drill tool. As the spear engages the drill tool, the shank of the tool passes into the socket 34, the force of the impact being sufficient to move the gripping 80 jaws 36 upwardly and into expanding position. As soon as the force of this impact is spent, the spring 37 re-acts to move the jaws 36 downwardly and into gripping position with respect to the tool shank so that when 85 the spear is lifted, the drill tool will be carried upwardly with the same. This operation having been completed, the gripping members are moved into biting engagement with the well casing by an actuation of the 90 tripping rod 29 in the manner previously described. Thus, the spear is in gripping relation with respect to the drilling tool and the well casing so that by lifting the 95 spear and the well casing either through the 100 medium of the drill line or the well casing, a removal of the well casing and the drilling tool is simultaneously effected. In practice, it is desirable that a suitable rope knife be lowered into the well casing and the drill 105 cable cut at a point adjacent the top of the spear, and the removal of the tool, spear and well casing effected by an elevation of the well casing.

From the foregoing operation, it will be 110 manifest that the withdrawal of the drilling tool and well casing may be expeditiously effected without the necessity of withdrawing the drill line through each and every joint of the well casing, as is the present 115 practice.

Although we have herein shown and described only one form casing and tool spear embodying our invention, it is to be understood that various changes and modifications may be made herein without departing from the spirit of the invention and the 120 spirit and scope of the appended claims.

What we claim is:

1. A combined casing and tool spear comprising, a body having an open bore therethrough adapted to receive a drill line, casing locking members movable to active and inactive positions, means for biasing the members to active position, means for latch- 125 130

- ing the members in inactive position against the action of said biasing means, said latching means being movable to a releasing position to release the locking members, a 5 socket detachably secured to the body, and means within the socket for permitting the insertion of the stem of a drilling tool therein and for locking the stem against withdrawal.
- 10 2. A combined casing and tool spear comprising a body having an open bore there-through adapted to receive a drill line and casing locking members movable to active and inactive positions, means for biasing 15 the members to active positions, means for latching the members in the inactive position against the action of said biasing means, said latching means being movable to release said locking members, a socket 20 detachably secured to the body and having a conical inner wall at one end thereof, gripping jaws seated within said frusto-conical portion, a spacing sleeve within the socket, and an expansible spring interposed 25 between the sleeve and jaws for biasing the latter in the direction of the conical wall for the purpose described.
3. A combined casing and tool spear comprising, a body bored to receive a drill line, 30 divergent surfaces formed on the opposite sides of the body and having grooves formed therein, casing locking members movable over said surfaces and having tongues engageable within said grooves, abutment keys 35 spanning said grooves for limiting the movement of the locking members in one direction over said surfaces, springs fitted within the body for biasing the members in the direction of the keys to effect an expansion of the members, a pair of locking 40 dogs pivotally supported within the body and normally engaging the ends of the members for locking the same against movement, a tripping rod normally interposed between 45 the dogs for maintaining the same in locking position, and a locking pin for maintaining said tripping rod in locking position 50 with respect to the dogs, said pin being adapted to be sheared to permit the removal of the rod from the body to release said dogs.
4. A combined casing and tool spear comprising, a body having an open bore there-through adapted to receive a drill line, 55 means adapted to lock the body against upward movement within a well casing, a socket detachably secured to the body, and means within the socket for permitting the insertion of the stem of a drilling tool there- 60 in and for locking the stem against withdrawal.
5. A combined casing and tool spear comprising, a body having an open bore there-
- through adapted to receive a drill line and including a wedge and a head, casing gripping members slidable on the wedge, springs fitted within said head and engageable with the gripping members for moving the latter into expanded position under the action of said wedge, means for latching the members 65 in a contracted position against the action of said springs, removable and releasable means for maintaining the latching means in latching position.
6. A combined casing and tool spear comprising, a body having an open bore there-through adapted to receive a drill line and including a wedge and a head, casing gripping members slidable on the wedge, springs fitted within said head and engageable with 70 the gripping members for moving the latter into expanded position under the action of said wedge, means for latching the members in a contracted position against the action of said springs, removable and releasable means for maintaining the latching means in latching position, and means carried by said head for receiving and gripping the stem of a drilling tool whereby when the spear is elevated within a well casing, the 75 drill tool is carried upwardly with the spear.
7. A combined casing and tool spear comprising, a body having an open bore there-through adapted to receive a drill line and including a wedge and a head, casing gripping members slidable on the wedge, springs fitted within said head and engageable with the gripping members for moving the latter into expanded position under the action of said wedge, means for latching the members 80 in a contracted position against the action of said springs, removable and releasable means for maintaining the latching means in latching position, and means carried by said head for receiving and gripping the stem of a drilling tool whereby when the spear is elevated within a well casing, the 85 drill tool is carried upwardly with the spear.
8. In a device of the character described, a body having an open bore extending axially thereof, locking means supported on 90 the body for movement from an inactive position to an active position, said means being adapted to engage the inner wall of a casing in which the body is disposed in such manner as to lock the body to the casing when the locking means is in active position and to permit of the body sliding in the casing when the locking means is in an inactive position, and frangible means for normally retaining the locking means in an 95 inactive position, said frangible means being of a nature to be rendered ineffective when a strong pull is exerted on the body.
